US00D337602S

United States Patent [19]

Chen

[11] Patent Number: Des. 337,602

[45] Date of Patent: ** Jul. 20, 1993

[54] CALCULATOR

[75] Inventor: Paul Chen, Taipei, Taiwan

[73] Assignee: Data Electrocraft Corp., Taipei, Taiwan

[**] Term: 14 Years

[21] Appl. No.: 889,295

[22] Filed: May 27, 1992

[52] U.S. Cl. D18/7
